UNITED STATES PATENT OFFICE

117,112

DESIGN FOR AN ELECTRIC HAMMER DRILL

John J. Roberts, Louisville, Ky.

Application October 26, 1938, Serial No. 80,673

Term of patent 14 years

To all whom it may concern:

Be it known that I, John J. Roberts, a citizen of the United States and a resident of Louisville, in the county of Jefferson and the State of Kentucky, have invented a new, original, and ornamental Design for an Electric Hammer Drill, showing my new design, of which the following is a specification, reference being had to the accompanying drawings, forming a part thereof.

In said drawings, Fig. 1 is a side elevational

view of an electric hammer drill, showing my new design; and

Fig. 2 is a front elevational view thereof.

The dominant features of my design reside in the portions shown in full lines in Figs. 1 and 2.

I claim:

The ornamental design for an electric hammer drill, as shown and described.

JOHN J. ROBERTS.
